UNITED STATES PATENT OFFICE

HANS PETERS, OF BERLIN, GERMANY, ASSIGNOR TO KNORR-BREMSE AKTIENGESELLSCHAFT, OF LICHTENBERG, BERLIN, GERMANY, A CORPORATION OF GERMANY

DUPLEX PUMP

Application filed April 23, 1930, Serial No. 446,681, and in Germany April 26, 1929.

This invention relates to duplex pumps of the kind in which the plungers or pistons in the two cylinders are in staggered arrangement so that one plunger is about midway in its operative stroke when the other plunger begins its operative stroke. It has been found that an undesirable increase of pressure takes place in the pressure pipe when the second plunger begins its stroke, especially in steam pumps where the exertion of force is at the maximum value at the beginning of the stroke and then declines according to a curve, and thus the force exerted by the first plunger is reduced at the middle of its stroke when the second plunger comes into operation with its full initial energy; but even in duplex pumps where the driving force is constant throughout the stroke, the same effect occurs when the second plunger comes into operation. The considerably greater pressure which is suddenly exerted on the liquid in the pressure pipe reacts upon the first plunger, which is about the middle of its stroke, so that the first plunger is momentarily brought to a standstill. Consequently the differential position of the two pump plungers in relation to each other is at this moment disarranged, whereby the object for which this differential position is designed, namely, the delivery of a flow of liquid under uniform pressure, is prejudicially affected. The object of the invention is to avoid this difficulty.

According to the invention a compensating device is provided whereby the increase in pressure exerted on the liquid by the second plunger coming into operation is converted into speed of flow. This device may be a nozzle in the pressure pipe, to which nozzle the currents of liquid arriving under pressure from the two pump cylinders are guided separately and combine within the diffuser of the said nozzle. This nozzle is connected by a suitable union with the water space of each cylinder and its diffuser opens into the pressure pipe, which may lead to a boiler or pre-heater.

In order that the said invention may be clearly understood and readily carried into effect, the same will now be further described with reference to the accompanying

drawing representing in elevation a duplex pump and in section a compensating device exemplifying the practical application of the invention.

The unions for connection with the pump cylinders A¹, B¹ are indicated at a and b respectively, and c indicates the diffuser which passes into the pressure pipe. It will be seen that a sudden increase in the pressure of the current arriving through either of the connections a, b is unable to act in a manner retarding movement upon the other current of liquid or upon the plunger impelling the same, but on the contrary, owing to the conversion of the pressure into energy of flow, causes a reduction in the resistance encountered by that current of liquid which is impelled by the plunger which is in the middle of its stroke. In the diffuser the energy of flow is again converted into pressure energy.

What I claim and desire to secure by Letters Patent of the United States is:—

1. In a duplex pump for discharging liquids to a pressure pipe alternately from each of the pump outlets, a nozzle in said pressure pipe having tapered passages each leading from one of the said outlets and converging into a constricted neck in the pressure pipe, whereby the increase of pressure exerted on the liquid already in the nozzle at the beginning of each discharge stroke of the pump is converted into speed of flow.

2. In a duplex pump for discharging liquids alternately from each of the pump outlets to a common pressure pipe, a diffuser located at the junction of said pipe with the connections from said outlets, said diffuser comprising a constricted neck and co-axial annular passages converging towards said neck, each of said passages being separately in communication with one of said connections, whereby the reaction of one pump plunger at the beginning of its stroke upon the other pump plunger which is simultaneously at the middle of its stroke is avoided.

3. In a duplex pump for discharging liquids alternately from each of the pump outlets to a common pressure pipe, a compensating device located at the junction of said pipe with the connections from said out-

lets to promote uniformity of the flow of liquid in said pressure pipe, said device comprising a tapered diffuser increasing in cross section towards the pressure pipe, a discharge 5 nozzle on one of said connections contracting in the direction of flow, an outer discharge nozzle on the other of said connections also contracting in the direction of flow and co- axially surrounding said first named nozzle, the cross-sectional area of the annular space 10 between said inner and outer nozzles being progressively reduced towards the narrow end of said diffuser.
